CLAIM

The ornamental design for food serving trays, as shown and described.

DESCRIPTION

FIG. 1 is a top isometric view of the food serving trays showing our new design.

FIG. 2 is a top isometric view of a serving tray component of the food serving trays.

FIG. 3 is a first side view thereof.

FIG. 4 is a second side view thereof.

FIG. 5 is a rear view thereof.

FIG. 6 is a front view thereof.

FIG. 7 is top view thereof.

FIG. 8 is a bottom view thereof.

FIG. 9 is a top isometric view of a serving insert component of the food serving trays.

FIG. 10 is a first side view thereof.

FIG. 11 is a rear view thereof.

FIG. 12 is a second side view thereof.

FIG. 13 is a front view thereof.

FIG. 14 is top view thereof.

FIG. 15 is a bottom view thereof.

FIG. 16 is a top isometric view of a serving panel component of the food serving trays.

FIG. 17 is a first side view thereof.

FIG. 18 is a second side view thereof.

FIG. 19 is a rear view thereof.

FIG. 20 is a front view thereof.

FIG. 21 is top view thereof; and,

FIG. 22 is a bottom view thereof.

Broken lines shown illustrate portions of the food serving trays that form no part of the claimed design.
